UNITED STATES PATENT OFFICE

164,575

READING MAGNIFIER

Edward C. Heard, Los Angeles, Calif.

Application March 23, 1951, Serial No. 14,604

Term of patent 14 years

(Cl. D57—1)

To all whom it may concern:

Be it known that I, Edward C. Heard, a citizen of the United States, residing at Los Angeles, in the county of Los Angeles and State of California, have invented a new, original, and ornamental Design for a Reading Magnifier, of which the following is a specification, reference being had to the accompanying drawing, forming part thereof.

Figure 1 is a top plan view of a reading magnifier showing my new design;

Figure 2 is a front elevational view;

Figure 3 is a rear elevational view;

Figure 4 is an end elevational view; and

Figure 5 is a bottom plan view,

I claim:

The ornamental design for a reading magnifier, as shown.

EDWARD C. HEARD.
